UNITED STATES PATENT OFFICE.

ARNOLD J. WEST, OF ABERDEEN, WASHINGTON.

DESIGN FOR A RAILROAD-TIE.

SPECIFICATION forming part of Design No. 29,683, dated November 15, 1898.

Application filed September 28, 1898. Serial No. 692,136. Term of patent 14 years.

To all whom it may concern:

Be it known that I, ARNOLD J. WEST, a citizen of the United States, residing at Aberdeen, in the county of Chehalis and State of Washington, have invented and produced a new and original Design for a Railroad-Tie, of which the following is a specification.

This invention relates to a new and original design for a railroad-tie; and it has for its object to provide a design of this character possessing merit and utility.

The leading feature of the design resides in a tie having an oblong rectangular body provided at its opposite lower side edges with downwardly-convergent flat inclined faces extending longitudinally from end to end thereof.

In the accompanying drawings, Figure 1 is a perspective view of a railroad-tie embodying the herein-described design. Fig. 2 is a bottom perspective view of the tie. Fig. 3 is a cross-section of the tie.

Referring to the accompanying drawings, the numeral 1 designates the oblong rectan-

gular body of the tie, having flat top and bottom faces 2 and 3, respectively, and also having the vertical side faces 4. At its lower side corners the tie-body 1 is chamfered or beveled, as indicated at 5, to form the oppositely-located inclined faces 6, which are downwardly convergent and extend longitudinally from end to end of the body. The said downwardly-convergent flat inclined faces 6 at the opposite lower side corners of the body meet the flat bottom face 3 and vertical side faces 4 in obtuse angles, as plainly shown in Fig. 3 of the drawings.

What is claimed is—

The design for a railroad-tie, herein shown and described.

In testimony that I claim the foregoing as my own I have hereto affixed my signature in the presence of two witnesses.

ARNOLD J. WEST.
